UNITED STATES PATENT OFFICE.

FISHER A. SPOFFORD AND MATTHEW G. RAFFINGTON, OF COLUMBUS, OHIO.

TOY PISTOL.

Specification forming part of Letters Patent No. **69,500**, dated October 1, 1867.

To all whom it may concern:

Be it known that we, FISHER A. SPOFFORD and MATTHEW G. RAFFINGTON, of Columbus, in the county of Franklin and State of Ohio, have invented a new Mode of Constructing a Toy Pistol for Shooting Marbles or other like Balls; and we do hereby declare that the following is a full and exact description thereof, reference being had to the accompanying drawings, and to the letters of reference marked thereon.

The nature of our invention consists in making a barrel and stock of wood or any other suitable material, with an aperture or hole at the top to receive the ball, and a piston or follower operated by a spring, made of steel or other suitable material, for operating the piston and driving the ball out, this pistol being intended for use in connection with the gallery patented to us on the 12th day of February, 1867.

To enable others skilled in the art to make and use our invention, we will proceed to describe its construction and operation.

Figure 1 is intended to show the pistol and the position of the piston F after being discharged. Fig. 2 is intended to show a sectional view of the pistol barrel and stock, giving a view and position of the parts when loaded.

A shows the inside of the barrel; B, the piston or follower; C, the spring for operat-

ing or driving the piston inwardly; D, the trigger; E, the aperture for admission of the ball when loading. F is a portion of the piston, which projects for operating or loading. g is the catch or dog for holding the piston back. h represents a small spring for holding the ball in position until discharged.

The operation: By taking hold of a portion of the piston (shown at F) and pulling it back until the inner end is dogged at g, then by inserting the ball at the aperture E, the pistol will be ready for firing or discharging. By operating the trigger D the piston B will be raised above the catch or dog, allowing the spring C to drive the piston forward and discharging the ball at the end of the barrel.

What we claim, and desire to secure by Letters Patent, is—

The toy pistol consisting of a barrel open at both ends, with the aperture E opening directly into the barrel near the breech, and having the spring h, located therein, as shown, with the piston B, operated by the spring C, and the trigger D, arranged to release the piston by elevating its front end, all as herein shown and described.

FISHER A. SPOFFORD.
MATTHEW G. RAFFINGTON.
